DOOR LOCK

Waldemar A. Endter, Long Beach, Calif.

Substitute for abandoned application July 24, 1931, Serial No. 552,812. Divided and this application July 27, 1936, Serial No. 92,865

13 Claims. (Cl. 292—192)

This is a substitute of my abandoned application on Door lock, Serial Number 552,812, filed July 24, 1931.

This invention relates to an improved door lock, 5 and particularly to a novel means of mounting a rotary latching element so that said element is retractable in the lock.

An object of my invention is to provide a novel 10 door lock of the rotary latching element type which rotary element is effectively held against rotation and so engages the rotary element as to hold the same tightly in the strike plate and thus holds the door against its stop.

Another object is to provide a novel means 15 whereby a lock of the character stated is held against accidental or forcible retraction of the lock.

A further object is to provide a novel wedge 20 construction for a rotary type of lock in which the wedges act against each other and against the lock case to prevent forcible retraction of the locking element.

Still another object is to provide a novel rotary 25 locking element in a door lock which will prevent vertical movement of the door.

A feature of my invention resides in the novel 30 multiple wedge construction whereby the rotary locking element is moved and held into proper locking position, and also is urged against the strike plate in such a manner as to hold the door tightly against the stop.

Other objects, advantages, and features of invention may appear from the accompanying drawings, the subjoined detailed description, and 35 the appended claims.

In the drawings:

Figure 1 is a longitudinal, sectional view of my lock, the high wedge block which engages the rotor being cut away. This section is taken on 40 line 1—1 of Figure 2.

Figure 2 is a sectional view taken on line 2—2 of Figure 1.

Figure 3 is an end view of my lock with the finish plate broken away to show the lock construction back of the same.

Figure 4 is an end view taken from the rear of the two wedges.

Figure 5 is a side elevation of the two wedges, one being shown in advance of the other.

Figure 6 is a longitudinal, sectional view of a 50 slightly modified form of lock, the section being similar to Figure 1.

Figure 7 is an end view of the same.

Figure 8 is an isometric view of the rotor yoke.

Figure 9 is a fragmentary, transverse, sectional view of still another modified form of lock.

Figure 10 is a fragmentary, sectional view taken on line 10—10 of Figure 9.

Figure 11 is a fragmentary, transverse, section- 60 al view of the door with my lock mounted there-

in, and the sill showing the method of operation of the rotary locking member.

Figure 12 is a top plan view of a modified type of rotary locking member.

Figure 13 is a side elevation of the same.

Figure 14 is a side elevation of the strike plate used in connection with the rotary element shown in Figures 12 and 13.

Referring more particularly to the drawings, the numeral 1 indicates a lock case, and in this case 10 I mount a U-shaped yoke 2 which is slidable horizontally in the case. The yoke 2 slides in recesses or groove-ways 3—3 which are formed in the lock case. A pair of pins 3'—3' extend from the yoke 2 and project into slots in the case 1. A 15 rotary locking element 4 is mounted on the forward end of the yoke 2 upon a pin or pins 5.

Within the lock case 1, and back of the rotary locking element 4, I provide a plurality of wedge blocks 6—7. These wedge blocks engage the 20 case 1 at the top and bottom thereof and are slidable in the case by a means to be further described. The blocks are each formed with tapered legs 8—9 respectively, the leg 8 being cut on a lesser taper than the leg 9. A roller 10 is 25 also provided at the forward edge of the block 7 for the purpose of lifting one of the wings 11 of the rotary locking element 4 after the wedge block with the lesser taper has slipped under that wing. This arrangement is shown in Figure 5. 30 The operation of the two wedge blocks 6 and 7 will be more completely described in a later part of the specification.

A pin 12 extends thru both of the wedge blocks 6 and 7, there being a hole in each of the blocks 35 to receive the pin, and a head 13 is formed on the outer end of the pin so that the wedge blocks cannot slide forwardly and entirely escape said pin. From the wedge blocks the pin extends rearwardly thru the yoke 2 and is attached to a 40 retracting member 14 which is slidable mounted in the case 1. The method of actuating the retracting element 14 is usual and well known in the art, and the detailed construction of this retracting means forms no part of this invention. 45

A spring 15 bears against the element 14 and against a stationary wall 16 thus urging the retracting element constantly in an outward direction. A spring 17 surrounds the pin 12 and extends from a wall 18 of the lock case to the 50 yoke 2 and thus urges this yoke outwardly so as to move the locking element 4 into proper locking position. Suitable stops are provided for the yoke 2 so as to prevent the yoke from being pushed entirely out of the case.

A pair of springs 19—20 bear against the wedge members 6—7 respectively to urge said wedges towards the locking element 4 and thus engage and hold the locking member in the following manner: When the door is closed, as shown in 55

60

Figure 11, the locking member 4 will engage the outer curved end of the strike plate 21. The yoke 2 will be moved inwardly into the case and against the tension of the spring 17. This inward movement of the yoke causes the same to engage a collar 22 on the pin 12, thus moving the pin inwardly and retracting the wedge members 6-7. As the locking member 4 rotates one of the wings 11 will engage the forward edges of the wedges 6-7 and move them inwardly against the tension of the springs 19-20. The wedges are slideable on the pin 12 as previously described, and consequently will move very readily.

When the rotary locking element 4 has reached the locking position in the strike plate, as shown in solid lines in Figure 11, the wedges 6-7 will be pushed under one of the wings 11 gradually rotating the locking member until the door is tightly held against the stop 23. Naturally the wedge having the lesser taper will first move forwardly under one of the wings of the member 4 and then as the wing is rotated, the wedge with the greater taper will enter and cause the locking element to be more tightly pressed against the strike plate. Thus it will be seen that the two different tapers on the wedge blocks will serve to more effectively and completely rotate the locking element into position, and a material saving in the length of the lock is thus provided because the bearing surface is transferred from one moving member to another, the final position of the wing engaged by the wedge blocks being above the wedge block having the lesser taper, as shown in Figure 1. As previously stated, the roller 10 guides the wing 11 on to the wedge block 7 with a minimum of friction, or the possibility of blocking the forward movement of said wedge block.

The adjacent and engaging surfaces of the wedge blocks 6-7 are cut at an angle as shown at 24 in Figure 4. The purpose of this arrangement is to cause a spreading apart of the wedge blocks if one of them is moved downwardly by the forcible rotation of the locking member 4 such as would occur if the door were forced. This spreading of the wedge blocks causes them to press tightly against the lock case and will offer a resistance to further retraction of the wedge blocks. Consequently they are held in locking position and the rotary locking element cannot be moved to force the door. However, when the door is opened by means of the usual handle or knob, the pin 12 pulls the wedge blocks rearwardly and the locking element is then free to rotate.

In Figures 6 and 7 the same general arrangement is shown as in Figures 1 to 5 inclusive, namely, the lock case 25, the winged or bladed rotary locking element 26 which is mounted upon a yoke 27, and a plurality of wedge blocks 28 which are slideably mounted in the lock case 25. A pin 29 extends rearwardly from the wedge blocks to an unlocking strap 30 which strap is retracted by the usual and well known means actuated by the handle or knob.

A coil spring 31 bears against the rear face of the strap 30 to urge the same forwardly, and the wedges are each urged forwardly by means of springs 32. In this instance, the lock case 25 is circular in form rather than rectangular, and the locking element 26 is slightly modified in shape in order to conform to the circular case as shown in Figure 7. The wedges 28 are slideable on the pin 29 in the same manner as pre-

viously described for the structures shown in Figures 1 to 5 inclusive.

In Figures 8 to 10 inclusive, an arrangement is shown whereby the wedges are quickly retracted and are moved by means of a lever action so as to provide a greater throw for the wedges. A yoke 33 is slidably mounted in the case 34. The bladed rotary locking element 35 is mounted on a pin 36 which is journaled in the yoke 33 and in the forward end of the same. In Figure 10 the rotary locking element is removed in order to more clearly show the wedges. A plurality of wedges 37 are mounted on a shaft 38, which shaft extends into slots 39 in the side of the yoke 33. These slots permit horizontal movement of the shaft in order to retract the wedges.

A link 40 extends from the shaft 38 to a second link 41, the latter link being pivoted either to the yoke 33 adjacent the top thereof or to the lock case. A retracting pin 42 is pivotally attached to the link 41 and extends rearwardly to the retracting plate 43. The retracting plate 43 is moved back and forth by means of a handle or knob in a usual and well known manner. This plate 43 is limited in its movement by contacting a stationary yoke 44.

A spring 45 bears against the plate 43 to urge the same forwardly, also a spring 46 bears against the yoke 33 to urge the same forwardly. It will be evident that when the pin 42 is retracted by the plate 43, that the wedges 37 will be quickly moved rearwardly away from the locking element 35 by reason of the levers or links 40-41.

As previously stated, the rotary locking element when engaging the strike plate, and when held by the wedges, will hold the door snugly against its stop. To prevent vertical movement of a door, I have provided a rotor or locking element as shown in Figures 12 and 13. The rotary locking element 47 is provided with a plurality of spiral or inclined blades 48. These blades fit into inclined grooves 49 in the strike plate 50. It will be evident that when the inclined or spiral blades are fitted in the grooves 49, that the door will be held against vertical movement. The modified locking element and keeper described in this paragraph form the subject matter of my Patent No. 1,902,547, issued March 21, 1933.

Having described my invention, I claim:

1. An improved door lock comprising a lock case, a yoke slidably mounted in said case, a rotary locking element journaled in the yoke, a plurality of blades on the rotary locking element, a plurality of wedges slideably mounted in the lock case, and means to retract said wedges, spring means bearing against said yoke, and spring means bearing against said wedges.

2. An improved door lock comprising a lock case, a yoke slidably mounted in said case, a rotary locking element journaled in the yoke, a plurality of blades on the rotary locking element, a plurality of wedges slideably mounted in the lock case, and means to retract said wedges, spring means bearing against said yoke, and spring means bearing against said wedges, each of said wedges having differently inclined wedge surfaces thereon.

3. An improved door lock comprising a lock case, a rotary locking element positioned adjacent one end of said case, blades on said rotary locking element, said blades protruding from the case, a pair of wedge blocks slideably mounted in the case, a tapered wedge surface on one of the blocks, the other block having a tapered wedge

surface of greater inclination than the first named block, spring means bearing against each of said blocks, and means to retract said blocks.

4. An improved door lock comprising a lock case, a rotary locking element positioned adjacent one end of said case, blades on said rotary locking element, said blades protruding from the case, a pair of wedge blocks slidably mounted in the case, a tapered wedge surface on one of the blocks, the other block having a tapered wedge surface of greater inclination than the first named block, spring means bearing against each of said blocks, means to retract said blocks, the abutting surfaces of said wedges being formed at an angle whereby said wedges are urged apart when said wedges are forcibly urged inwardly by pressure exerted on said locking element.

5. An improved door lock comprising a lock case, a yoke slidably mounted in said case, a rotary locking element journaled in the yoke, a plurality of blades on the rotary locking element, a pair of wedges slidably mounted in said case, means to retract said wedges, a spring bearing against each of the wedges to urge the same outwardly, a spring bearing against said yoke to urge the same outwardly, a tapered surface on one of said wedge blocks, the second wedge block having a tapered surface of lesser inclination than the first.

6. An improved door lock comprising a lock case, a yoke slidably mounted in said case, a rotary locking element journaled in the yoke, a plurality of blades on the rotary locking element, a pair of wedges slidably mounted in said case, means to retract said wedges, a spring bearing against each of the wedges to urge the same outwardly, a spring bearing against said yoke to urge the same outwardly, a tapered surface on one of said wedge blocks, the second wedge block having a tapered surface of lesser inclination than the first, the abutting surfaces of said wedges being formed at an angle whereby said wedges are urged apart when said wedges are forcibly urged inwardly by pressure exerted on said locking element.

7. An improved door lock comprising a lock case, a yoke slidably mounted in said case, a rotary locking element journaled in said yoke, a plurality of blades on the locking element, a pair of wedge blocks slidably mounted in the case, a retracting pin engaging both of said wedges, means to retract said pin whereby said wedges are moved inwardly, said wedges having inclined surfaces thereon adapted to engage the blades of the locking element, one of said wedge surfaces being greater than the other, spring means engaging said yoke to urge the yoke outwardly, the contacting face of said wedge blocks being formed on an angle whereby the wedge blocks are forced apart and against the lock case when pressure is exerted on the locking element.

8. An improved door lock comprising a lock case, a yoke slidably mounted in said case, a rotary locking element journaled in the yoke, a plurality of blades on the rotary locking element, a plurality of wedges slidably mounted in the lock case, and means to retract said wedges, spring means bearing against said yoke, and spring means bearing against said wedges, each of said wedges having differently inclined wedge

surfaces thereon, and a roller journaled on the forward end of said wedge blocks, said roller being adapted to contact the rotary locking element as said wedge blocks move outwardly.

9. An improved door lock comprising a lock case, a yoke slidably mounted in said case, a rotary locking element journaled in said yoke, a plurality of outwardly extending blades on said locking element, a wedge block adapted to engage the rotary locking element whereby said locking element is held against rotation, a shaft on which said wedge block is mounted, a link attached to said shaft, means pivotally mounting said link in the lock case, a retracting pin, said pin being pivotally attached to said link, means to retract said pin whereby the link is swung and the wedge block is retracted, a spring engaging said wedge block to urge the same outwardly, and a spring engaging the yoke to urge the yoke outwardly.

10. An improved door lock comprising a lock case, a yoke slidably mounted in said case, a rotary locking element journaled in the yoke adjacent the outer end thereof, a plurality of blades extending from the rotary locking element, a wedge block adapted to engage one of the blades to hold the locking element against rotation, a shaft extending thru the wedge block, a link attached to the shaft, a second link pivotally attached to the first named link, means pivotally mounting the last named link in the case, a retracting pin, said pin being pivotally attached to second link, means to retract said pin whereby said links are swung and the wedge block is retracted, a spring engaging said wedge block to urge the same outwardly, and a spring engaging the yoke to urge the yoke outwardly.

11. An improved door lock comprising a lock case, a yoke slidably mounted in said case, a rotary lock element journaled in the yoke, a plurality of blades on the rotary locking element, wedge slidably mounted in the lock case and bearing against said case, an inclined wedge surface on the wedge, said wedge surface being adapted to engage one of the blades of the rotary locking element, means to retract said wedge, spring means bearing against the yoke and spring means bearing against said wedge.

12. An improved door lock comprising a lock case, a yoke slidably mounted in said case, a rotary locking element journaled in the yoke, a plurality of blades on the rotary locking element, dogging means mounted in the case and engageable with said rotary locking element, whereby said locking element is held against reverse rotation, and means to retract said dogging means, a spring means bearing against the yoke, a spring means bearing against said dogging means.

13. An improved door lock comprising a lock case, a yoke slidably mounted in said case, a rotary locking element journaled in the yoke, a plurality of blades on the rotary locking element, dogging means mounted in the case and engageable with said rotary locking element, whereby said locking element is held against reverse rotation, and means to retract said dogging means, a spring means bearing against the yoke, a spring means bearing against said dogging means, said dogging means bearing against the yoke.
